RATCHET WRENCH CONSTRUCTION

John Ekern Ott, Hinsdale, Ill., assignor to
Punch-Lok Company, Chicago, Ill., a partnership

Application June 5, 1947, Serial No. 752,596

9 Claims. (Cl. 192—45.1)

1

Ratchet wrenches of the general character here contemplated are commonly constructed of two stamped sheet metal handle members with pawl and ratchet mechanism housed between the two handle members, and the latter being secured together by two or three rivets located at spaced points along the length of the handle members. One of these rivets is usually the pivot pin for the pawl, and it is relied upon to hold the handle sections together at the ratchet end of the handle where most of the working stresses or strains occur in the wrench. In order that the handle be able to withstand forces which occur in normal uses of the wrench, especially at the ratchet end thereof, it has been the practice to make these handles of sheet metal of relatively heavy gauge or thickness, for example in the neighborhood of .065 inch. Notwithstanding the relatively heavy weight of metal which has been used, it has been found that wrenches embodying the indicated construction frequently fail and become inoperative due to spreading of the ratchet enclosing end of the handle structure.

The main object of the present invention is to provide a wrench construction which will effectively prevent failure of the wrench by spreading or splitting of the ratchet supporting end of the handle structure. Another object is to provide a structure which will permit the use of substantially lighter metal in the handle structure than has heretofore been possible, while at the same time providing adequate strength. Still another object is to provide an arrangement for indicating the proper application of the wrench to a part for turning such part in a predetermined direction.

Other objects and advantages will be understood by reference to the following specification and accompanying drawing in which there is illustrated a ratchet wrench embodying a selected form of the invention.

In the drawing:

Fig. 1 is a plan, certain portions being broken away and shown in section to more clearly illustrate the construction.

Fig. 2 is a section on an enlarged scale on the line 2—2 of Fig. 1, and

Fig. 3 is a more or less schematic representation of the manner in which parts of the wrench are assembled.

The wrench herein disclosed embodies a ratchet member 1 having oppositely projecting hubs 2 and 3, the hubs and ratchets being provided with an axial hole 4 of hexagonal or other form for cooperating with a nut or shaft to be turned

2

through the agency of the wrench. The ratchet 1 is rotatably mounted in a handle 5 which comprises a pair of stamped sheet metal members 6 and 7 which are of substantially like form.

Each of the handle members 6 and 7 have peripheral flange portions 8 and 9 respectively which are adapted to engage one another as indicated in Fig. 2 to thereby space portions of the members within which are mounted the ratchet 1, a pawl 10 and a spring 11. Portions of the handle members 6 and 7 are offset inwardly as indicated at 12 and 13 respectively to meet in face to face engagement as best shown in Fig. 2.

For rotatably supporting the ratchet 1, the handle members 6 and 7 are respectively provided with lateral outwardly projecting annular flange portions 14 and 15 which have free end portions 16 and 17 respectively of inwardly tapering or truncated cone shaped form. The inside diameter of the flange portions 14 and 15 is made to rotatably receive the external diameter of the bearing hubs 2 and 3 so as to permit the ratchet to rotate freely in the handle structure. To receive the inwardly offset end portions of the annular flanges resulting from the inwardly tapered free end portions, the hubs 2 and 3 are respectively provided with annular grooves 18 and 19.

In one practical embodiment of the wrench, the inwardly tapered portions 16 and 17 are disposed at an inwardly tapering angle of 30°, and the free ends of said portions are substantially squared as shown. The grooves 18 and 19 are formed in the hubs 2 and 3 to provide walls disposed at angles approximately corresponding to the respectively adjacent inside walls 20 and 21 of the tapered end portions, and the end walls 22 and 23 of said tapered portions.

The ratchet 1 is, of course, provided with peripheral teeth as best shown in Fig. 1, and the pawl 10 has one end formed for cooperative engagement with said teeth to permit the ratchet to turn in one direction relative to the handle and to lock the ratchet against turning in the other direction. The pawl 10 is pivotally mounted on a shouldered rivet 24 which serves to properly space the adjacent portions of the handle members so as to permit free movement of the pawl between said handle members. The spring 11 is housed in a recess 25 provided in the pawl and between the handle members 6 and 7, the handle member 6 being provided with a spring housing formation in the form of an outwardly offset transversely extending hollow rib 26. The rivet 24 is headed over on the outside

of the handle members 6 and 7 as shown so as to thereby prevent spreading of the handle members, and rivets such as indicated at 27 and 28 are passed through other portions of the handle member to secure the same in assembled relationship to each other.

It will be seen that in the described constructions, forces exerted by the ratchet 1 on the adjacent end portions of the handle elements 6 and 7 and which tend to separate the ratchet-supporting end portions of the handle members from each other are effectively resisted by the end portions of the ratchet hubs which are engaged by the end walls 22 and 23 of the inwardly offset end portions of the bearing flanges. Hence, neither the rivet 24 nor the rigidity of the respective handle elements is depended upon to withstand the ratchet forces which tend to split the handle.

According to the present invention, the annular bearing flanges 14 and 15 with their respective inwardly offset free end portions are completely formed before the handle sections are assembled with the ratchet element. In order to permit assembly of the part, the handle elements are preferably made of sheet steel having a temper (known in the trade as No. 3 temper) which leaves in the metal a degree of elasticity which is sufficient to permit the inwardly offset free end portion of the bearing flange to be temporarily expanded incident to the forcing of the handle member and its bearing flange over the hub of the ratchet in the manner represented in Fig. 3.

As shown in Fig. 3, the ratchet 1 is supported in a jig 29 while the handle member 6 (or 7) is placed over the ratchet element with the hub 2 thereof entering the bearing flange as far as possible. A pressure member 30 is then brought to bear against the handle element to force it downwardly into assembled relation to the ratchet whereupon the inwardly offset free end portion 16 of the handle member is forcibly expanded to pass over the outer or free end portion 31 of the ratchet hub until said free end portion 16 is permitted to snap into the groove 18. The elasticity of the metal employed in forming the handle sections should, of course, be sufficient to permit the indicated enlargement or stretching of the reduced diameter of the free end portions of the bearing flanges, and to cause the same to resume their normal reduced diameter positions when brought into registry with the receiving grooves of the ratchet hubs. After one handle section is assembled with the ratchet, the other section may be similarly assembled preferably after positioning the pawl and spring in the handle element which is first assembled with the ratchet. After the handle sections are both assembled with the ratchet, the heading of the rivets 24, 27 and 28 may be completed.

By employing tempered metal of the character indicated for forming the side plates, the described snap action assembling portion is facilitated, this being considerably more desirable than a swaging operation to form the inwardly offset portions of the bearing flanges as a part of the assembling operation. Such swaging operations would, for practical purposes, require the employment of softer metal which would in turn require the use of heavier metal in order to secure the desired strength and rigidity.

In a practical embodiment of the structure, stamped metal having a thickness of about .042 inch has been employed, this thickness providing a wrench structure which is considerably lighter in weight than prior art ratchet wrenches of the

same overall size, and the stiffness of the handle, that is its strength against bending, has been found to be entirely adequate. The thickness of the handle member from the outside of one section 5 to the outside of the other has been reduced to about $\frac{2}{3}$ of the thickness of comparable wrenches in prior conventional constructions so that a much less cumbersome tool is provided. The provision of the outwardly adequate support 10 for rotatably supporting the ratchet without danger of any angular crimping or cramping action while also facilitating the interlocking of the handle sections with the ratchet element as explained.

In the arrangement described, the abrupt angles of the ends 22 and 23 of the bearing flange portion are such that there is no significant tendency of said ends to be cammed outwardly over the larger extremities of the ratchet bearing hubs while the angular disposition of the walls 20 and 21 of said angularly disposed end portions is relatively small so that these walls are effective to cooperate with the inwardly disposed wall portions 25 of the flange to provide a bearing support for the ratchet.

The provision of the outwardly offset spring relief as shown at 26 in one handle section only is advantageous not only because it permits the use of a relatively large diameter spring, but also because it provides an indicator for indicating the proper application of the wrench for rotating an element in a predetermined direction. This indicator is not only visibly operative but also operative by feel under circumstances when it is not practical to see its location.

Various changes in the described structure may be made without departing from the invention.

I claim:

1. A wrench comprising a ratchet having a bearing hub projecting therefrom, and a handle 40 provided with an annular bearing flange rotatably receiving said hub, said annular bearing flange having a portion of less internal diameter than the diameter of said hub and the latter having, intermediate its ends, an annular groove receiving said flange portion so as to interlock said ratchet and handle, said handle being of metal having sufficient elasticity to permit said reduced diameter flange portion to be temporarily enlarged incident to forcible passage of said hub through said flange portion and to cause said flange portion to contract and enter said groove to interlock said ratchet and handle as aforesaid.

2. A wrench according to claim 1 in which the reduced diameter bearing flange portion is provided by a frusto-conical end portion of the bearing flange.

3. A wrench according to claim 1 in which the reduced diameter bearing flange portion is provided by a frusto-conical end portion of the bearing flange, and in which the free end wall of said frusto-conical portion, and the corresponding wall portion of the groove in the ratchet hub, are disposed at an angle which is nearer to right-angular relationship to the axis of the ratchet than to parallel relationship thereto.

4. A ratchet wrench comprising a ratchet having oppositely projecting bearing hubs, and a handle having a pair of sheet metal members 70 each provided with an annular bearing flange rotatably receiving one of said ratchet hubs to rotatably support said ratchet between said handle members, said bearing flanges each having a portion of less internal diameter than the diameter of the respective hubs received in the flanges

and said hubs each having, intermediate its ends, an annular groove receiving the respective reduced diameter flange portions so as to interlock said handle members and ratchet against separation.

5. A ratchet wrench according to claim 4 in which the sheet metal of which said handle members are made has sufficient elasticity to permit the reduced diameter flange portions to be temporarily enlarged incident to the forcible passage of said hubs through said flange portions and to cause said enlarged flange portions to contract and enter said grooves to interlock the handle members and ratchet as aforesaid.

6. A wrench according to claim 5 in which the reduced diameter flange portions are provided by frusto-conical end portions of the bearing flanges and in which the free end walls of said frusto-conical portions and the corresponding walls of said grooves in the ratchet hubs are disposed at an angle which is nearer to right-angular relationship to the axis of the ratchet than to parallel relationship thereto.

7. A ratchet wrench comprising a ratchet having oppositely projecting bearing hubs, a handle having a pair of sheet metal members each provided with an outwardly extending annular bearing flange rotatably receiving one of said ratchet hubs to rotatably support said ratchet between said handle members, said bearing flanges each having a portion of less internal diameter than the diameter of the respective hubs received in the flanges and said hubs each having, intermediate its ends, an annular groove receiving the respective reduced diameter flange portions so as to interlock said handle members and ratchet against separation, rivets uniting said handle members at points spaced from said ratchet, a pawl pivotally mounted on one of said rivets and cooperating with said ratchet to prevent relative rotation between said handle and said ratchet in one direction, and a spring housed between said handle members and bearing on said ratchet to yieldingly maintain the same in cooperating relationship to said ratchet.

8. A ratchet wrench comprising a ratchet having oppositely projecting bearing hubs, a handle having a pair of sheet metal members each provided with an outwardly extending annular bearing flange rotatably receiving one of said ratchet hubs to rotatably support said ratchet between

said handle members, said bearing flanges each having a portion of less internal diameter than the diameter of the respective hubs received in the flanges and said hubs each having, intermediate its ends, an annular groove receiving the respective reduced diameter flange portions so as to interlock said handle members and ratchet against separation, rivets uniting said handle members at points spaced from said ratchet, a pawl pivotally mounted on one of said rivets and cooperating with said ratchet to prevent relative rotation between said handle and said ratchet in one direction, and a spring housed between said handle members and bearing on said ratchet to yieldingly maintain the same in cooperating relationship to said ratchet, one only of said handle members being provided with an outwardly projecting formation providing an inside recess in said handle member for housing said spring, said outwardly projecting formation serving also as an indicator for determining proper positioning of the wrench for operation in a predetermined direction.

9. A ratchet wrench comprising a ratchet having a bearing hub projecting therefrom, a handle provided with an annular bearing flange rotatably receiving said hub, said hub having an annular groove, and said annular bearing flange having an integral portion projecting into said groove, said groove being located intermediate the ends of said bearing hub so that integral portions of the hub on opposite sides of said groove engage said groove-entering portion of said bearing flange to thereby interlock said ratchet and handle, and a pawl carried by said handle and engaging said ratchet to lock the same against rotation in one direction relative to said handle.
